BOBBIN CASE OPENER DRIVING MECHANISMS

Gregory Goebel, Trumbull, Conn., assignor to The Singer Manufacturing Company, Elizabeth, N. J., a corporation of New Jersey

Application March 4, 1954, Serial No. 414,049

2 Claims. (Cl. 112—184)

This invention relates to a driving mechanism for a sewing machine loop-taker and, more particularly, to a gear drive conjointly actuating a vertical axis rotary hook and a bobbin-case opener mechanism.

It is an object of this invention to provide a gear drive which may be incorporated within a frame or saddle in which both the hook and the bobbin case are carried as a unit.

It is a further object of this invention to provide a gear drive of the above character in which the timing of the rotary hook with respect to the needle may be adjusted readily and without disturbing the timed relation between the rotary hook and the bobbin-case opener mechanism.

With the above and other objects and advantages in view as will hereinafter appear, this invention comprises the devices, combinations and arrangements of parts hereinafter described and illustrated in the accompanying drawings in which:

Fig. 1 is a side elevational view of a portion of a sewing machine, partly in vertical section and having my invention applied thereto;

Fig. 2 is an enlarged top plan view of one hook saddle of the sewing machine illustrated in Fig. 1;

Fig. 3 represents a vertical sectional view of the hook saddle taken substantially along line 3—3 of Fig. 2; and

Fig. 4 represents a vertical sectional view of the hook saddle taken substantially along line 4—4 of Fig. 2.

Referring particularly to Fig. 1, the present invention has been embodied in a two-needle lock-stitch sewing machine. This machine has a frame comprising a bed 10 from one end of which rises a standard 11 which supports a bracket-arm terminating in a sewing head 12 which overhangs the bed. Journaled for endwise reciprocation in the sewing head 12 is a needle-bar 13 which has clamped at its lower end two needles 14 and 15 that are spaced from each other lengthwise of the bed 10. Also journaled for vertical movement in the head 12 is a spring depressed presser-bar 16 carrying at its lower end a conventional presser-foot 17.

A throat-plate 18, which is carried by the bed beneath the presser-foot 17, is apertured to accommodate penetration by the needles and is slotted in the usual manner to receive a feed-dog 19 which is supported beneath the bed and given rising and falling movements by a feed-lift eccentric 20 which is carried by the usual bed-shaft 21. In addition to these rising and falling movements, an adjustable eccentric 22 also carried by the bed-shaft 21 serves, as is well known in the art, to impart advance and return movements to the feed-dog transversely of the bed to feed the material being stitched with respect to the needles.

The mechanism for reciprocating the needles is not shown in the drawings, however, any conventional needle-reciprocating means may be employed. The bed-shaft 21 is driven, as by a belt 23, in timed relation with the needle-reciprocating means, that is, with the bed-shaft completing one revolution for each cycle of needle reciprocation.

2

The feed-dog, therefore, will complete one cycle of work advancing motion for each reciprocation of the needles.

The bed 10 is apertured, as at 24, at each side of the throat-plate and is provided at each side with a slide 5 cover-plate 25 which may be withdrawn to expose the stitch-forming instrumentalities beneath the bed. These stitch-forming instrumentalities, which are complementary to the respective needles 14 and 15 in the formation of lock-stitches, are two loop-takers 26 and 27 comprising 10 conventional vertical axis rotary hooks each having a needle-thread loop-seizing beak 28. Journaled in each of the rotary hooks 26 and 27 is a bobbin-case carrier 29 which is adapted to receive a bobbin (not shown) upon which is wound the lower or locking thread. The rotary hook in the usual way is adapted to cast a loop of needle-thread about the locking thread on the bobbin, thereby to form the usual lock-stitch. Each bobbin-case carrier 29 is formed with a rotation-restraining nose 31 which projects between spaced stop lugs 32—32 depending from 15 the throat-plate 18 to prevent the bobbin-case carrier from rotating with the hook. Each bobbin-case carrier is also formed with a radially extending ear 33 that forms a part 20 of the bobbin-case opener mechanism which, as will be presently described, serves periodically to rock the bobbin-case carrier so as to provide a clearance space for passage of the loop of needle-thread between the rotation-restraining nose 31 and the stop lugs 32—32.

Each of the rotary hooks 26 and 27 is carried in a separate support bracket or saddle 34 and 35, respectively, and each of the saddles also carries a bobbin-case 30 opener mechanism. As shown in Fig. 2, the saddles are each adapted to be supported beneath the bed 10 and to that end each is provided with a split boss 36 clamped by a screw 37 upon one of the bushings 38 and 39 in which 35 the bed-shaft 21 is journaled. The saddles are also slotted, as at 40, each to accommodate a fastening screw 41 which is threaded into the machine bed. When the screws 37 and 41 are loosened, therefore, the saddles may be relocated lengthwise of the bed, as for instance, to reposition 40 the hooks for cooperation with a different lateral spacing of needles 14 and 15.

The hook saddles, as best illustrated in Fig. 4, are each formed at one side of the split collar 36 with a concavity 45 extending horizontally across the saddle and defining in the saddle vertically spaced bearing lugs 43 and 44. The saddles are also provided each with a shallow oil pan 45 which is fitted beneath the saddle and has a gasket 46 therebetween to provide a lubricant-containing reservoir 47.

50 Since the arrangement of the rotary hook, the bobbin-case opener mechanism, and the driving mechanism therefore are similar in each of the hook saddles save that each is of the opposite hand, a description of the right hand hook saddle 35 of Fig. 1, which is illustrated in detail in

55 Figs. 2, 3 and 4 will apply equally well to both saddles. The rotary hook 27 is carried by a hook shaft 50 which is journaled on a vertical axis in bearings 51 and 52, one in each of the vertically spaced bearing lugs 43 and 44 of the hook saddle. Adjacent the hook shaft and also 60 journaled on a vertical axis in bearing bushings 53 and 54 is a bobbin-case opener driving shaft 55. A crank pin 56 formed at the upper extremity of the opener driving shaft 55 is connected by a link 57 to one arm of a bell-crank lever 58 that is journaled for oscillatory movement on a raised boss 59 which surmounts the saddle 35. A finger 65 70 60 which is secured to the bell-crank lever 58 is disposed periodically to engage the ear 33 which projects from the bobbin-case carrier and in this manner to rock the bobbin-case and shift the nose 31 clear of the stop lugs 32—32 for unobstructed passage of the needle-thread therebetween.

In the present invention, the rotary hook 27 and the

driven by the actuating shaft 21 by means of a set screw 65 seated in an elongated key-way or groove 63 formed in the bed-shaft so that gear 61 may be shifted conveniently along the shaft without angular shift of the gear about the shaft whenever lateral adjustment is made of the position of the hook saddle.

Meshing with the spiral driving gear 61 is a spiral pinion 64 which is carried by the hook shaft 50 and is made fast thereto by set screws such as that shown at 65. The pinion 64 is one-half the size of the driving gear 61 so that the hook will be rotated at twice the speed of the bed-shaft 21 and, therefore, the hook will partake of two revolutions for each cycle of reciprocation of the needles as is conventional in rotary hook machines. The set screws 65 of the pinion 64 are accessible by virtue of a slot 66 formed in the bearing lug 43 of the hook saddle, as shown in Fig. 4, and the timing of the hook with respect to the needle may be accomplished by loosening the set screws 65 and adjusting the rotary hook and the hook shaft with respect to the pinion 64.

Carried on the hook shaft 50 beneath and independently of the pinion 64 is a bobbin-case opener driving spur gear 67 which is made fast to the hook shaft as by set screws 68. Meshing with the driving spur gear 67 is a spur gear 69 which is made fast to the bobbin-case opener drive shaft 55, as by set screws 70. Gear 69 is preferably twice the size of the opener driving gear 67 so that the bobbin-case opening finger 69 will be oscillated into operative engagement with the ear 33 on the bobbin-case carrier with the same frequency as the needle reciprocation, i. e., once for every two revolutions of the rotary hook.

In the operation of a rotary hook with a bobbin-case opening mechanism, a definite timing relationship must exist between the rotation of the hook and the oscillation of the opener finger. This will be self evident when it is understood that the thread is cast about the bobbin-case by the hook and, therefore, the action of the hook dictates the proper instant at which the bobbin case should be opened or shifted clear of the rotation-restraining lugs. In the present invention the timing of the bobbin-case opener mechanism with the rotary hook is insured since the hook shaft 50 and the opener drive shaft 55 are interrelated with a positive mechanical driving connection in the form of the set of gears 67 and 69. In contrast with all of the prior bobbin-case opener driving constructions, the present invention provides a timing connection between the rotary hook and the bobbin-case opener mechanism which once properly set, as by adjustment of gears 67 and 69 on their respective shafts, will not be disturbed by any of the other adjustments to the hook or the hook saddle which may be necessary for proper stitch formation.

One of the most common of these adjustments is the lateral adjustment of the entire hook saddle as when the hook saddle is to be shifted along the bed shaft 21 to accommodate a change in spacing between the needles. This adjustment is accomplished by loosening the saddle-fastening screw 41 and the clamp screw 37 as well as the set screw 62 of the spiral driving gear 61 and then by shifting the saddle together with the spiral driving gear 61. During this adjustment the timed relation between the hook and the opener mechanism remains undisturbed.

Still another adjustment, that of the hook timing with respect to the reciprocation of the needle, may be accom-

plished in two ways neither of which alter the timing between the hook and the opener mechanism when the machine is equipped with the present improvement. Timing of the hook with the needle may be accomplished by loosening the set screw 65 and angularly adjusting the spiral pinion 64 on the hook shaft. Fine adjustments of hook timing with respect to the needle may also be effected by shifting the spiral driving gear 61 lengthwise of the bed-shaft for a small amount. Because of the spiral shape of the gear teeth, this bodily shifting of the gear 61 provides for a micrometer adjustment of hook timing.

Since none of the above described adjustments of the hook position or timing affects the meshing interconnection of gears 67 and 69, the present invention provides a construction in which the bobbin-case opener mechanism when properly timed will remain in the desired timed relation with the hook.

Having thus set forth the nature of the invention, what I claim herein is:

1. A rotary hook mechanism assembly adapted to be detachably secured as a unit to a sewing machine having a rotary actuating shaft and a driving gear mounted on said actuating shaft, comprising, a supporting saddle, a rotary hook-shaft journaled in said supporting saddle, a first gear mounted on said hook-shaft and adapted to mesh with said driving gear on said actuating shaft, a rotary hook carried by said hook-shaft, means for securing said first gear in a selected one of a plurality of positions angularly of said hook-shaft, a bobbin case carrier journaled in said rotary hook, an opener-finger supported on said saddle for movement into and out of engagement with said bobbin case carrier, a rotary opener-shaft journaled in said saddle and operatively connected to said opener-finger, a gear on said opener-shaft, a second gear mounted on said hook-shaft and meshing with the gear on said opener-shaft, and means for securing said second gear in selected position angularly of said hook-shaft.

2. A rotary hook mechanism assembly adapted to be detachably secured as a unit to a sewing machine having a horizontally disposed rotary actuating shaft and a driving gear mounted on said actuating shaft, comprising, a supporting saddle, a rotary hook-shaft journaled vertically in said supporting saddle, an upper gear mounted on said hook-shaft and adapted to mesh with said driving gear on said actuating shaft, means for securing said upper gear in a selected one of a plurality of positions angularly of said hook-shaft, a rotary hook carried by said hook-shaft, a bobbin-case carrier journaled in said rotary hook, an opener-finger supported on said saddle for movement into and out of engagement with said bobbin-case carrier, a rotary opener-shaft journaled in said saddle in substantially parallel relation with said hook-shaft and operatively connected to said opener-finger, a gear on said opener-shaft, a lower gear mounted on said hook-shaft below said upper gear and meshing with the gear on said opener-shaft, and means other than that for adjustably securing said upper gear for securing said lower gear in a selected one of a plurality of positions angularly of said hook-shaft.
